(57) **CLAIM**

The ornamental design for a bench towel, as shown and described herein.

DESCRIPTION

FIG. 1 is a front and side perspective view of a bench towel showing my new design; with the upper portions shown in a folded, draped position;

FIG. 2 is a front view thereof;

FIG. 3 is a back view thereof;

FIG. 4 is a left side view thereof;

FIG. 5 is a right side view thereof;

FIG. 6 is a top side view thereof; and,

FIG. 7 is a bottom side view thereof.

The short dot-dot broken lines represent stitching.
